ATTACHMENT FOR CHIMNEY TOPS

Walter E. Wilhite, Spokane, Wash.

Application May 23, 1955, Serial No. 510,308

3 Claims. (Cl. 98—67)

My present invention is an attachment for chimney tops, flues, and the like, and is particularly adapted for improving the draft conditions within a chimney.

The greatest problem experienced with chimneys and flues is poor draft conditions. This may either be in lack of draft or too much draft. The lack of draft is caused by air currents being deflected down the chimney by higher objects such as buildings, surrounding hills, etc., or a less often recognized cause wherein the flue gases are chilled or cooled before they have opportunity to pass up and out of the chimney, thus creating a down pressure. Obviously, when the flue gases are cold, it is necessary for the fire to push a column of heavy air ahead of them in order to escape up the chimney. This is the primary cause of certain types of fireplaces and other flues smoking when the fire is first kindled. This downdraft or "no draft" obviously causes the smoke and gases to escape from the firebox. These poor draft conditions have a secondary undesirable effect which results in causing the chimney or flue to collect carbon deposits which tend to ignite and burn out periodically.

It is therefore one object of this invention to provide an attachment for chimneys which will eliminate all of the aforementioned difficulties.

Another object of this invention is to provide an attachment for chimney tops which may be easily installed without the use of tools or cement, and is particularly constructed and arranged to anchor itself to the chimney when applied thereto.

Still another object of the invention lies in the provision of an attachment for chimney tops which may be installed thereupon, regardless of the variations in sizes and shapes among a number of chimneys.

These and other objects of the invention will become apparent during the course of the following description.

In the accompanying drawings, I have shown a preferred form of the present invention for the purpose of illustration only and not for the purpose of limiting the scope of my present invention, except insofar as it is defined in the appended claims. Like numerals are employed to designate like parts in the accompanying drawings, wherein:

Figure 1 is a perspective view of a chimney top upon which one of my chimney attachments is installed;

Figure 2 is a vertical cross section substantially on the plane of line 2—2 of Figure 1 and upon an enlarged scale;

Figure 3 is a horizontal cross section taken on the plane indicated at line 3—3 of Figure 2 and upon a further enlarged scale;

Figure 4 is a further enlarged fragmentary vertical cross section as at the plane of line 2—2 of Figure 1 showing the insulation and retaining band;

Figure 5 is a plan view of a circular form attachment;

Figure 6 is a view similar to Figure 3 of the circular attachment shown in Figure 5; and

Figure 7 is a perspective view of the attachment shown in Figures 5 and 6.

2

Referring now more particularly to the drawings, it will be seen that the numeral 10 denotes a chimney of the type which is commonly constructed of brick for residential purposes, and the numeral 11 denotes my improved attachment for chimney tops.

5 The attachment preferably is formed having an upwardly tapered circumferentially continuous inner shell 12 which is produced from a flexible resilient metal such as galvanized iron, and it will be seen that the shell is open at its upper and lower ends. The shell 12 is circumferentially continuous and may be square, rectangular, or round, as desired.

Secured to the upper end of the shell 12 by means of an interlocking rolled or welded sealed connection, I. 15 provide a downwardly flared skirt 13 which is provided with an inturned cylindrical flange 14 which extends downwardly into the open upper end of the shell 12 and by a rolled connection or weld rigidly unites the shell and the skirt against displacement, one from the other.

It will be noted in Figure 2 that the shell and the skirt 20 have therebetween a progressively increasing space toward their lower ends, and also the shell is substantially longer than the skirt. In actual practice, the height of the skirt is 12 inches while the length of the shell is 24 inches. These dimensions, however, may vary according to the size of the chimney or flue upon which the attachment is to be used. The lower end of the shell 12 is substantially greater in diameter than the width of the flue of the chimney 10 so that it will conform to the 25 cross-sectional configuration of the flue as seen in Figure 3.

On its external peripheral face, the shell 12 is provided with an upwardly tapered sleeve 15 of insulation material such as fiberglass or vermiculite. This insulation sleeve 15 is maintained in proper encircling relationship to the shell 12 by means of an annular band 16 of flexible resilient metal which has a depending flange 17 at its lower end disposed on a shorter radius than the balance of the band and in face to face engagement with the peripheral face of the sleeve 12. The band is secured to the sleeve 12 by means of staples 18 or other convenient securing means, and confines the insulation sleeve 15 in face to face engagement with the sleeve 12.

In Figures 5, 6, and 7, I have shown the attachment 45 with a frusto-conical skirt 13, and in this structure the sleeve 12 will also initially be frusto-conical. However, the body material of the sleeve 12 and the band 16 is such that it may be shaped by hand to fit into a square or rectangular flue (as seen in Figure 7), and its resiliency attempts to return the sleeve to its normal circular configuration and thus the resilient pressures exerted by the lower end of the inner shell 12 assist in securing the attachment to the chimney and substantially seal therebetween.

50 It will be noted that no cement or other adhesive material is required for securing the attachment to the chimney since the inner shell 12 is of such a length that it will extend into the flue liner 10a of the chimney and its own resiliency will maintain the attachment thereon by 55 frictional engagement therewith.

If found desirable, a sealing compound may be applied at the lower marginal edge of the skirt 13 as indicated at 19 to prevent moisture from flowing under the attachment, and gases which may possibly escape between the flue liner 10a and the skirt 12 by reason of a crack or other deformity may be confined against discharge thereunder.

The reduced mouth or upper end of the attachment, as well as the upwardly tapered skirt 13, prevent down-drafts in the chimney by deflecting outside airflow upwardly as it strikes the skirt 13, and by increasing the velocity of flue gases as they discharge through the upper

opening of the sleeve 12 by reason of its reduced diameter. This causes a better flue action, eliminating the deposit of carbon to a great extent on the walls of the flue, preventing smoking from the firebox, and because of the better flue action, facilitating combustion of the fuel.

Having thus described my invention, I claim:

1. The combination with a chimney having a tubular flue, of an attachment therefor comprising a downwardly flared open ended circumferentially continuous skirt having its lower end resting upon the upper end of said chimney; said skirt having an inturned cylindrical flange at its upper end defining a reduced opening therein; an open ended upwardly tapered resilient flexible annular inner shell coaxially arranged with relation to said skirt and having its open upper end secured in encircling sealing engagement with said flange; said shell being substantially longer than said skirt and extending downwardly therefrom into said flue and its lower end being of sufficient diameter with respect to said flue to conform thereto and frictionally grip and seal at its lower end to said flue by reason of the pressures exerted by the resiliency of said shell; and an insulating sleeve encircling said shell in face to face relationship and terminating spaced from the ends thereof.

2. The combination with a chimney having a quadrilateral tubular flue, of an attachment therefor comprising

5 ing an open ended upwardly tapered resilient flexible initially circular inner shell extending downwardly into the flue of said chimney and being sufficiently greater in diameter at its lower end than the width of said flue to conform thereto and be secured therein by the pressure applied to the walls of the chimney flue by the resiliency of said shell; a downwardly flared open ended circumferentially continuous skirt secured at its upper end in encircling sealing engagement with said inner shell and defining a reduced opening; said skirt being substantially shorter than said shell and resting upon the upper end of said chimney to support said attachment.

3. The invention as defined in claim 2 and further characterized by an insulating sleeve encircling said shell in face to face relationship and terminating spaced from the ends thereof.
